UNITED STATES PATENT OFFICE.

GEORGE J. LUBBERING, OF CINCINNATI, OHIO.

AUTOMATIC UNCOUPLING DEVICE.

SPECIFICATION forming part of Letters Patent No. 368,157, dated August 9, 1887.

Application filed May 9, 1887. Serial No. 237,593. (No model.)

To all whom it may concern:

Be it known that I, GEORGE J. LUBBERING, a resident of Cincinnati, in the county of Hamilton and State of Ohio, have invented 5 certain new and useful Improvements in Automatic Uncoupling Devices, of which the following is a specification.

This invention is especially adapted to be used upon coal-cars as employed upon elevated 10 trackways. It is adapted to be used on all cars which are attached to cables, and more especially to that class which are attached to one end of a cable.

The object of my invention is to automatically 15 uncouple a car as it arrives at the point of destination, all of which will be set forth in the description of the accompanying drawings, making a part of this specification, in which—

Figure 1 is a plan view of the elevated track-way, and the frame of a car with my improvement attached. Fig. 2 is a perspective view of the uncoupling device. Fig. 3 is a top plan view of Fig. 2.

1 represents the trackway; 2, the ties or sleepers supporting the track; 3, the car-trucks; 25 4, the cable for pulling the car; 5, the car-axle; 6, the coupling-bar provided with slot 7, into which the eye 8 of the cable-swivel enters. 9 represents the other portion of the swivel attached to the cable 4.

10 represents an oscillating lever pivoted to the axle by a bolt, 11.

12 represents a lug or downwardly-projecting arm of the lever.

35 13 represents a draw-bar carrying the bolt or pin 14 on its inner end. This pin passes through eyes formed in the end of the draw-bar 6, which is preferably made by doubling over the metal and welding the two parts together, 40 as shown in Fig. 2.

15 represents a spring-compressing-rod. It is supported by ear 16 on the lever 10 and by ear 17 on draw-bar 6.

18 represents the head, forming the spring-seat at one end, and the ear 17 forms the other seat of the coiled spring 19. The spring 19 normally holds the lever 10 and draw-bar 13

in the position shown in Figs. 1 and 2, and the bolt 14 passes through the eyes of the draw-bar and the swivel-eye 8, in which position 5c the car is securely coupled to the cable 4.

In order to automatically uncouple the car, a tripping-block, 20, is placed in proper position upon the ties of the track, so that the lug 12 of lever 10 will strike the inclined edge 55 21 and, as the car passes along, will pull the lever 10 and the draw-bar 13 into the position shown in Fig. 3, releasing the coupling or connection of the car to the cable. The spring automatically pulls the coupling-bar back into 60 position.

In Fig. 1 the illustration represents the two ends of an elevated trackway for coal-cars, and two tripping-blocks 20 are in position to uncouple the car at each end of its route while 65 in motion, and allow the car to go forward to its destination.

This contrivance is very cheap, simple, and effective, and avoids danger to the operator in uncoupling the car.

Having described my invention, what I claim as new is—

1. The uncoupling device composed substantially of the lever 10, coupling-arm 13, draw-bar 6, slotted to receive the eye of the 75 cable, and the tripping-block 20, attached to the track, substantially as specified.

2. In combination with the axle of a car, the slotted draw-bar 6, the coupling-arm 13, the lever 10, and the spring and rod attached to 80 the draw-bar and lever, substantially as specified.

3. In combination with the uncoupling device consisting of the lever 10, draw-bar 6, the coupling-arm 13, the compressing-spring 19, 85 operated by the lever 10, and tripping-block 20, substantially as specified.

In testimony whereof I have hereunto set my hand.

GEORGE J. LUBBERING.

Witnesses:

J. WATSON SIMS,
